UNITED STATES PATENT OFFICE.

HENRY C. LEWIS, OF CHARLESTON, WEST VIRGINIA, ASSIGNOR TO CHARLESTON ELECTRICAL SUPPLY COMPANY, A CORPORATION OF WEST VIRGINIA.

PRESS.

Application filed February 20, 1922. Serial No. 538,141.

To all whom it may concern:

Be it known that I, HENRY C. LEWIS, a citizen of the United States, residing at Charleston, in the county of Kanawha and 5 State of West Virginia, have invented a new and useful Press, of which the following is a specification.

This invention is a device for simultaneously applying pressure in a plurality of 10 directions.

One of the objects of the invention is to provide a device which may be used for simultaneously gripping or pressing articles of quadrilateral cross sections, on all four 15 sides; for simultaneously gripping articles of circular or other cross section at four points; or which may be employed for pressing and molding plastic material by pressures which are approximately equal in all 20 directions. A further object is to provide four jaws or members, so mounted that they are caused to simultaneously open or close, according to the direction of movement, in such manner that a true rectangular opening of increasing or diminishing size is insured at all times. A further object is to 25 provide means by which the parts may be adjusted, to provide an opening of true square cross section, or of oblong section as 30 may be desired. A further object is to provide jaws so mounted that they will normally move in unison, and means whereby one side of the opening may be temporarily displaced, to permit insertion and removal 35 of the article being operated upon. A further object is to provide a device for pressing the slot portion or cell of armature, stator and rotor coils for electric motors and generators, which will be adjustable to a 40 large variety of shapes, sizes and lengths of coils, and which will simultaneously close up equally on all four sides of the coil, thereby avoiding open corners capable of catching loose wires or insulation.

45 The invention will be hereinafter fully set forth and particularly pointed out in the claims.

In the accompanying drawing:

50 Figure 1 is a side elevation illustrating an apparatus constructed in accordance with the invention. Figure 2 is a top plan view thereof. Figure 3 is a longitudinal cross section view. Figure 4 is a rear view. Figures 5 and 6 are diagrammatic views illus-

trating the operation. Figure 7 is a detail 55 sectional view illustrating the mounting of the adjustable upper jaw. Figure 8 is a similar view illustrating the mounting of the adjustable lower jaw. Figure 9 is a view illustrating slight modifications.

Referring to the drawing, 10 designates a body portion, provided with a base 11, having means by which it may be secured to a suitable table or other support. The sides of said body are provided with guides 12. 60 The forward end of said base is provided with an inclined portion which supports the stationary jaw or member 13, the ends of which overlap the sides of said body, said jaw being supported at an angle of forty-five degrees with respect to the guides 12. Said body portion is also provided with a flat bearing portion 14, also arranged at an angle of forty-five degrees with respect to the guides 12 and at right angles to the stationary member, said bearing portion having a T-shaped slot 15 formed therein, arranged transversely of the body 10. On each side of the body 10 is a lug, in which is 65 adjustably mounted an abutment screw 16, 70 which may be locked in any adjusted position by a suitable lock nut, as shown.

Resting upon the top of the body 10, and engaging the guides 12, is a carrier 17, provided with inclined guides 18, arranged at 75 an angle of forty-five degrees with respect to the guides 12, having their lower ends arranged opposite to portions of the stationary member 13. Adjustably mounted upon the guides 18, is a casing 19, which is adjusted 80 by means of screws 20, mounted in the top of the carrier 17, and operated simultaneously by means of a hand wheel 21, through the medium of a cross shaft 22 and beveled 85 gears 23. A suitable clamp C may be employed to normally prevent rotation of said hand wheel. Slidably mounted in the casing 19 is a movable member 24, the lower 90 end of which is normally pressed into abutting contact with the stationary member 13, by means of springs 25 encircling guide rods 26, and interposed between the upper 95 end of the jaw and the top wall of the carrier 17. Downward movement of said member 24 is limited by stops 27, carried by the projecting ends of the guide rods 26, positioned to contact with the top wall of the carrier 17.

The carrier 17 may be shifted along the guides 12 in any suitable manner, such as by compressed air, steam, hydraulic, hand, or other power. In the drawing, for illustrative purposes, an actuating screw shaft 28 is shown as mounted in the body 10, and engaged with the carrier 17. Upon the projecting end of said screw shaft 28 is secured a spur gear 29, meshing with a pinion 30, mounted on a shaft 31, extending below the base 11 to the front of the machine, and provided with a hand wheel 32.

Secured in a normally fixed position to the front of the carrier 17 and extending over the front face of the member 24, is a member 33. As shown, this member is provided with a flange 34, slotted to receive securing screws 35, which may engage any of a series of holes 36, in the front face of the casing 19. In practice, members 33 of different sizes may be substituted one for the other, for purposes which will be later described.

Slidably mounted upon the bearing member 14 are two guides 37, each provided with a clamping screw 38, having a head working in the T-slot 15. Slidably mounted between the guides 37 is a member 39, which is normally held in contact with the member 33, by means of springs 40, encircling the guide rods 41, which project through the ends of the carriers, said springs being interposed between the ends of the carriers and the member 39. Upward movement of the member 39, is limited by stop members 42, carried by the ends of the guide rods 41. Said rods are connected to a lever 43, actuated by a pedal link 44, so that member 39 may be moved independently of the other members.

In practice, the stationary member 33 is removable, so that such members for the various different lengths of coils to be pressed, may be substituted one for the other. The members 13 and 24 are of fixed width, and determine the maximum length of cell on the slot portion of the coil that can be pressed. The member 39 has its four edges shaped to correspond with different sizes of member 33. The operator first selects the member 33 corresponding to the size of cell which it is desired to make, and attaches the same to the casing 19. The member 39 is then adjusted so that the edge of the same which corresponds to the width of the member 33, which has been selected, will come in contact with said member 33. To change the position of the member 39, the clamping screws 38 are first unscrewed, and the stop members 42 are removed from the guide rods 41. The member 39 may then be withdrawn from the guides 37, and the latter adjusted to the proper width. The member 39 is then placed back in engagement with the carriers 37, with the proper edge ex-

tending upwardly. The stop members 42 are then connected with the guide rods, and the guides 37 locked in place by the screws 38. The member 33 is then placed in position.

In operation, the hand wheel 32 is actuated to move the carrier 17, toward and from the stationary member 13. As said carrier 17 travels forwardly or backwardly the lower end of the member 24 will slide up or down, as the case may be, upon the inclined face of the stationary member 13, and at the same time the member 39, will correspondingly slide upon the inclined end face of the member 33. Inasmuch as the movement of the members 13 and 24 is simultaneous with the movement of member 33, and the carrier 17, the adjustment is effected with respect to a fixed position P, i. e., the upper edge of member 13. Therefore, the manipulation of the hand wheel 32, will cause the parts to produce a recess of approximately perfect rectangular cross section, the size of which will vary with the location of the carrier 17 with respect to the position P. If it is desired to change the shape of the recess from a true square to an oblong cross section, such change is effected by adjusting the position of the casing 19, upon the guides 18, of the carrier 17, by means of the hand wheel 21, and the adjusting screws 20. It will be noted that the guides 18 are provided with scale marks to guide the operator in making adjustments for different sizes. The guides 12 are also provided with scale marks to aid in adjusting the carrier 17. If the machine is to be continuously operated for a given size of opening, the abutment screws 16 are adjusted to bring the carrier 17 to a stop, in a position to produce the cavity of the desired size. Said abutment screws are held in their adjusted positions by the lock nuts.

If it is desired to press one turn, or open end coils of the wave or series winding type, the clamping screws 38 are loosened, and the jaw member 39 and its carriers 37 are shifted either to the right or left, until the outer edge of said member 39 comes flush with the contiguous edges of the jaw 13 and member 24. A stationary member 33 is then set even with the member 39, and the parts are secured in the adjusted position.

The body 10 may be cast hollow and fitted with an inlet pipe 43, and outlet pipe 44, through which steam may be passed, when it is desired to hot press coils, or one or more holes 45 may be cored through close to the face of member 12, and steam passed through them for the same purposes. It is obvious that the same arrangement used for hot pressing of steam may be used for cold pressing by passing water through the body 10 instead of steam. If desired, the member 13 may be separate, and bolted or screwed to

the body 10 in suitable manner, and beneath said member, the body 10 may be provided with a chamber 46, to receive an electric heating element 47. (See Figure 9.)

5 The advantages of the invention will be readily understood by those skilled in the art to which it appertains. It will be noted that the recess-forming members are so arranged, that articles of quadrilateral cross 10 section may be simultaneously gripped on all four sides, or articles of other cross section may be gripped simultaneously at four points, and pressures applied to the articles, which pressures will be approximately equal 15 in all directions. An important advantage lies in the fact that the members are so mounted, that they are caused to open or close in such manner, that an approximately true square opening is insured at all times, 20 but that if desired the shape may be changed to that of an oblong section. A further advantage is that the members must normally move in unison, and yet means are provided by which one side of the opening may be 25 temporarily displaced, to permit of insertion and removal of the article to be operated upon. The invention is particularly useful in pressing the slot portion or cell of armature, stator and rotor coils of electric 30 motors and generators, and is adjustable to a large variety of shapes, sizes and lengths of coils. It is to be understood that although the device specifically illustrated and described, is primarily designed for pressing 35 the slot portion or cell of the armature, stator or rotor coils of electric motors and the like, the same has been selected for illustrative purposes only. In other words, the invention is not limited to any such use, but 40 comprehends any assembly of the generic elements which comes within the terms of the appended claims.

Having thus explained the nature of the invention and described an operative manner 45 of constructing and using the same, although without attempting to set forth all of the forms in which it may be made, or all of the forms of its use, what is claimed is:—

50 1. A press of the character described comprising a plurality of members one of which is normally fixed, the other members being movable with respect to the fixed member, whereby a quadrilateral opening is provided 55 when the members are separated.

2. A press of the character described comprising a plurality of members one of which is normally fixed, the other members being movable with respect to the fixed member, 60 whereby a quadrilateral opening is provided when the members are separated, and means for simultaneously imparting movement to all of said movable members.

65 3. A press of the character described comprising a plurality of members relatively

disposed to form an enclosed quadrilateral space, means simultaneously acting on the members to uniformly increase or decrease the dimensions of said space, and means acting upon said members to change the normal 70 shape of said quadrilateral space.

4. A press of the character described comprising a plurality of members one of which is normally fixed, the other members being movable with respect to the fixed member, 75 whereby a quadrilateral opening is provided when the members are separated, and means for adjusting the normally fixed member to change the normal shape of said opening.

5. A press of the character described comprising a plurality of members one of which is normally fixed, the other members being movable with respect to the fixed member, whereby a quadrilateral opening is provided when the members are separated, means for 80 simultaneously imparting movement to all of said movable members, and means acting independently of the member moving means for adjusting the fixed member to change the normal shape of said opening. 90

6. A press of the character described comprising a body, a plurality of members supported by said body one of which is normally fixed, the others being movable with respect to one edge of the fixed member, whereby a 95 quadrilateral opening is provided when the members are separated, and means carried by the body for effecting relative adjustment of said members.

7. A press of the character described comprising two sets of members, each set consisting of a pair of relatively movable members, one member of each set bearing against a member of the other set, and means for adjusting all of the members of one set, and one member of the other set with respect to a 105 fixed position on the remaining member of the last mentioned set, whereby a quadrilateral opening is provided when the members are separated. 110

8. A press of the character described comprising two sets of members each consisting of a movable and a relatively stationary member, the movable member of each set bearing against the stationary member of the other set, and means for adjusting the stationary members toward and from each other. 115

9. A press of the character described comprising a plurality of members, one of which is normally fixed and provided with a face arranged at an angle of forty-five degrees to the horizontal, the other members being movable with respect to one edge of the fixed member, in quadrilateral relation with said member, whereby a quadrilateral opening is provided when the members are separated. 120

10. A press of the character described comprising a fixed member, a second member 125 movable at an angle relative thereto, a car-

rier also movable relative to said fixed member, and a pair of members mounted in the carrier and co-operating with the first mentioned members to provide a quadrilateral space when said members are separated.

11. A press of the character described comprising a fixed member, a second member movable at an angle relative thereto, a carrier also movable relative to said fixed member, a pair of members mounted in the carrier and co-operating with the first mentioned members to provide a quadrilateral space when said members are separated, and means for adjusting said carrier relative to the fixed member, whereby the dimensions of said space are increased or diminished.

12. A press of the character described comprising a body provided with a fixed member, a second member supported by said body and movable relative to the fixed member, an adjustable carrier guided by said body and movable relative to said fixed member, and a pair of members mounted in the carrier and co-operating with the first mentioned members to provide a quadrilateral space when said members are separated.

13. A press of the character described comprising a body provided with a fixed member, a second member arranged at right angles to the operative face of the fixed member and movable relative thereto, a carrier guided by said body and movable relative to the fixed member, a movable member mounted in the carrier and abutting against the working surface of the fixed member, and a member fixed to said carrier and having a working surface at right angles to the last mentioned movable member, positioned to overhang and abut against the contiguous end of the first mentioned movable member.

14. A press of the character described comprising a fixed member, a second member movable relative thereto, a carrier also movable relative to the fixed member, a casing supported by said carrier, a movable member mounted within said casing and abutting said fixed member, and a member normally fixed to the exterior of said casing and co-operating with the other members to provide a quadrilateral space when said members are separated.

15. A press of the character described comprising a fixed member, a second member movable relative thereto, a carrier movable relative to the fixed member, a casing supported by said carrier, a movable member slidably mounted in said casing, means yieldably holding the last mentioned movable member in engagement with the fixed member, and a member normally fixed to said casing and co-operating with the other members to provide a quadrilateral space when said members are separated.

16. A press of the character described comprising a fixed member, a second mem-

ber movable relative thereto, a carrier movable relative to the fixed member, a casing supported by said carrier, a movable member slidably mounted in said casing, means yieldably holding the last mentioned movable member in engagement with the fixed member, a member normally fixed to said casing and co-operating with the other members to provide a quadrilateral space when said members are separated, and guide means for said spring pressed member having means limiting the movement of said member in one direction.

17. A press of the character described comprising a fixed member, a second member movable at an angle relative thereto, a carrier also movable relative to said fixed member, a pair of members mounted in the carrier and co-operating with the first mentioned members to provide a quadrilateral space when said members are separated, and means operating upon one of the members mounted in the carriage to change the normal shape of said space.

18. A press of the character described comprising a fixed member, a second member movable relative thereto, a carrier also movable relative to the fixed member, a casing supported by said carrier, and a pair of members supported by said casing and co-operating with the first mentioned members to provide a quadrilateral space when said members are separated, and means for adjusting said casing to change the normal shape of said space.

19. A press of the character described comprising a fixed member, a second member movable relative thereto, a carrier also movable relative to said fixed member, a casing supported by said carrier and adjustable relative to said fixed member, and a pair of members supported by the casing and co-operating with the first mentioned members to provide a quadrilateral space when said members are separated.

20. A press of the character described comprising a fixed member, a second member movable relative thereto, a carrier also movable relative to said fixed member and provided with guides, a casing engaging said guides, a pair of members supported by the casing and cooperating with the first mentioned members to provide a quadrilateral space when said members are separated, and means for adjusting said casing to change the normal contour of said space.

21. A press of the character described comprising a fixed member, a second member movable relative to said fixed member and provided with guides, a casing engaging said guides, a pair of members supported by the casing and cooperating with the first mentioned members to provide a quadrilateral space when said members are separated, ad-

justing screws mounted in said carrier and engaging said casing, and means for actuating said adjusting screws.

22. A press of the character described comprising a body provided with a fixed member, a second member supported by said body and movable relative to said fixed member, a carrier guided by said body and movable relative to the fixed member, and a pair of members mounted in the carrier and co-operating with the first mentioned members to provide a quadrilateral space when said members are separated.

23. A press of the character described comprising a fixed member, a second member movable at an angle relative thereto, a carrier also movable relative to said fixed member, a pair of members mounted in the carrier and co-operating with the first mentioned members to provide a quadrilateral space when said members are separated, and adjustable means for limiting movement of the carrier toward said fixed member.

24. A press of the character described comprising a body provided with guides, a fixed member carried by said body, a second member carried by said body movable relative to the fixed member, a carrier engaging said guides, a pair of members mounted in the carrier and co-operating with the first mentioned members to provide a quadrilateral space when said members are separated, and an adjusting screw mounted in said body and engaging said carrier, whereby the latter may be adjusted relative to said fixed member.

25. A press of the character described comprising a fixed member, a second member movable at an angle relative thereto, a carrier also movable relative to said fixed member, and a pair of members mounted in the carrier and co-operating with the first mentioned members to provide a quadrilateral space when said members are separated, one of the members mounted in the carrier being removable to permit substitution of corresponding members of different sizes.

26. A press of the character described comprising a fixed member, a second member movable relative thereto, a carrier movable relative to the fixed member, a casing supported by said carrier, a movable member mounted in said casing and engaging the fixed member, and a member removably secured to the exterior of said casing in a position to engage one end of the first mentioned movable member.

27. A press of the character described comprising a fixed member, a second member movable relative thereto, a carrier movable relative to the fixed member, a casing supported by said carrier, a movable member mounted in said casing and engaging the fixed member, a member removably se-

cured to the exterior of said casing in a position to engage one end of the first mentioned movable member, said casing and said removable member having complementary means whereby said removable member may be secured in any desired position transversely of the casing, and means whereby the first mentioned movable member may also be adjusted transversely of the device.

28. A press of the character described comprising a fixed member, a support mounted in juxtaposition therewith, a second member laterally adjustable on the support and free to move at right angles to the fixed member, a carrier also movable relative to the fixed member, and a pair of members mounted in the carrier and co-operating with the first mentioned members to provide a quadrilateral space when said members are separated.

29. A press of the character described comprising a fixed member, a support mounted in juxtaposition therewith, a second member laterally adjustable on the support and free to move at right angles to the fixed member, a carrier also movable relative to the fixed member, and a pair of members mounted in the carrier and co-operating with the first mentioned members to provide a quadrilateral space when said members are separated, one of the members mounted in said carrier being adjustable laterally to register with the first mentioned movable member.

30. A press of the character described comprising a fixed member, a support mounted in juxtaposition therewith, guide members laterally adjustable upon the support, a second member mounted in said guide members and movable relative to the fixed member, a carrier also movable relative to the fixed member, and a pair of members mounted in the carrier and co-operating with the first mentioned members to provide a quadrilateral space when said members are separated, one of the members mounted in said carrier being laterally adjustable to register with the first mentioned movable member.

31. A press of the character described comprising a fixed member, a support mounted in juxtaposition therewith and provided with a slot, guide members provided with adjusting screws engaging said slot, a second member mounted in said guide members and movable relative to the fixed member, a carrier also movable relative to the fixed member, and a pair of members mounted in the carrier and cooperating with the first mentioned members to provide a quadrilateral space when said members are separated.

32. A press of the character described comprising a fixed member, a spring pressed

member movable relative thereto, means limiting the movement of said spring pressed member under the tension of its spring means, a second spring pressed member normally engaging said fixed member, means limiting the movement of the second spring pressed member under its spring tension, and a fourth member co-operating with the first mentioned members to provide a quadrilateral space when said members are separated.

33. A press of the character described comprising a fixed member, a spring pressed member movable relative thereto, means limiting the movement of said spring pressed member under the tension of its spring means, a second spring pressed member normally engaging said fixed member, means limiting the movement of said spring pressed member under its spring tension, a fourth member co-operating with the first mentioned members to provide a quadrilateral space when said members are separated, and means for relatively adjusting said members to change the normal contour of said space.

34. A press of the character described comprising a body provided with a fixed member, a spring pressed member movable relative to said member, means limiting movement of said member under its spring tension, a carrier guided by said body, a spring pressed member mounted in said carrier and normally engaging said fixed member, means limiting movement of the last mentioned spring pressed member under the tension of its spring pressure, and a member normally fixed to said carrier and co-operating with the other members to provide a quadrilateral space when the members are separated.

35. A press of the character described comprising a plurality of members relatively disposed to form an enclosed quadrilateral space, means simultaneously acting on the members to uniformly increase or decrease the dimensions of said space, and means whereby one of the movable members may be moved independently of the other members.

36. A press of the character described comprising a plurality of members, one of which is provided with a face arranged at an angle of forty-five degrees to the horizontal, the other members being movable with respect to one edge of the fixed member, in quadrilateral relation with said member, whereby a quadrilateral opening is provided when the members are separated, and means whereby one of the movable members may be moved independently of the other members.

37. A press of the character described comprising a fixed member, a second member movable at an angle relative thereto, a carrier also movable relative to said fixed member, a pair of members mounted in the carrier and co-operating with the first mentioned members to provide a quadrilateral space when said members are separated, and means for moving the second member independently of the other members.

38. A press of the character described comprising a plurality of members one of which is normally fixed and the others being movable with respect to the fixed member, whereby a quadrilateral opening is provided when the members are separated, and means for heating said normally fixed member.

39. A press of the character described comprising a fixed member, a second member movable at an angle relative thereto, a carrier also movable relative to said fixed member, and a pair of members mounted in the carrier and cooperating with the first mentioned members to provide a quadrilateral space when said members are separated, one of the members mounted in the carrier being removable to permit substitution of corresponding members of different sizes, said second member being reversible and provided with a plurality of working faces conforming to removable members of different sizes.

In testimony whereof I have hereunto set my hand.

HENRY C. LEWIS.
